(57) **CLAIM**

I claim the ornamental design for a knee brace, as shown and described.

DESCRIPTION

FIG. 1 is an enlarged perspective view of a knee brace;
FIG. 2 is an enlarged left view of thereof;
FIG. 3 is an enlarged rear view thereof; and
FIG. 4 is a bottom view thereof; and,
FIG. 5 is a top view thereof.
All other broken lines depict portions of the knee brace and
form no part of the claim.
